UNITED STATES PATENT OFFICE.

EVERETT C. MORGAN AND JOHN E. MORGAN, OF CAMDEN, AND GEORGE P. PINZKA,
OF MANTUA, NEW JERSEY.

LEATHER-GLAZING MACHINE.

Application filed April 15, 1925. Serial No. 23,375.

This invention relates to leather glazing machines, and an object of the invention is to provide a machine which will glaze a relatively large area of leather in proportion to 5 the area of a hide or leather glazed by leather glazing machines of the approved types now in use.

In the approved types now in use, a single glass or agate cylinder is used and the hide 10 is moved about upon the supporting platform and engaged by the glazing agate causing several movements of the hide before it is completely glazed.

It is an object of the present invention to 15 provide a machine wherein an entire hide may be glazed by a single manual operation, namely, that of feeding it to the glazing machine which includes a plurality of staggeredly arranged agates or glazing cylinders 20 arranged so as to glaze the entire area of the hide.

Another object of the invention is to provide a glazing machine as specified, in which 25 manually operated means are provided for regulating the pressure of the glazing cylinders upon the leather.

Other objects of the invention will appear in the following detail description, and in the accompanying drawings wherein:—

30 Figure 1—is a side elevation of the improved glazing machine showing parts thereof in section.

Figure 2—is an end elevation of the improved glazing machine.

35 Figure 3—is a detail section on the line 3—3 of Figure 2.

Figure 4—is a horizontal section through the glazing machine taken on the line 4—4 of Figure 2.

40 Figure 5—is an enlarged detail illustrating the mounting of one of the glazing cylinder or agates.

Figure 6—is a detail view.

Referring more particularly to the drawings, the improved leather glazing machine includes a supporting structure 1 which has a table 2 supported thereabove and hingedly connected at one end by hinges 3 to the supporting structure. Expansion spiral springs 45 4 are provided at the edges or sides of the supporting structure 1 and they engage against the undersurfaces of the horizontal portions 5 of the substantially Z irons which are attached to and extend along the side

edges of the table 2, and they engage against the horizontal portions of the Z irons 6 which are attached to the supporting structure 1. The springs 4 one of which is positioned one at each side of the table structure—55 are coiled about suitable bolts 7 which extend through the Z irons 5 and are held against movement relative to the Z irons and the table 2 by suitable nuts 8. The bolts 7 project downwardly through pivotally mounted 60 spring tensioning members 9 which are pivoted as shown at 10, to suitable brackets carried by the table structure and have their outer ends beveled, as shown at 11. Slidable 65 wedges 12 are slidably supported by the sides of the supporting structure 1 and they are connected by suitable angle plates 13 to a cross bar 14, which extends across beneath the supporting structure. The cross bar 14 is connected intermediate its ends by means of angled bars 15 to a yoke 16, which yoke is 70 provided with an internally screw threaded head 17 through which the feed screw 18 extends. A suitable crank lever 19 is connected to the feed screw 18 for rotating the feed screw and for moving the cross bar 14 and the wedge members 12 laterally across the supporting structure 1. The wedge members 12 move in slots 20 in the side rails 21 of the supporting structure 1—and their beveled 75 surfaces 22 riding over the beveled surfaces 11 of the spring tensioning members 9 will move the table 2 on its hinges towards or from the upper surface of the supporting structure, tensioning or lessening the tension 80 upon the springs 4 which resiliently urge the table structure 2 outwardly from the supporting structure 1.

The table structure 2 has its upper surface cut at inclines—at each edge longitudinally, 85 as shown at 22, in Figure 5 of the drawings, and its surface is faced with a facing 23 of leather.

Bearing structures 24 are supported by suitable supporting structure 25 above the table 2, and at each end of the table. A shaft 26 is rotatably supported by the bearings 24, and it carries a drum 27 which drum has a plurality of agates or glazing cylinder 28 attached to its outer surface in longitudinally extending rows. The cylinders 28 in one longitudinal row are disposed staggeredly with respect to the cylinders in the other rows, so that the cylinders in each row bridge 90 100 105

the space between the cylinders in the adjacent rows. The cylinders 28 are constructed of glass, agate or other suitable material, such as used in the glazing of leather, and they are attached to the drum 27 by suitable bracket or bearing structure 29 each of which comprises separable sections 30 clamped together by suitable bolts 31 to permit removal of the cylinders whenever necessary.

10 1e The table structure 2 is reinforced by the angle irons 32 which engage across the edges and beneath the bottom of the wood body of the table for bracing it, and the table is further braced by the transverse bolts 33 extending therethrough. The bolts 33 are removable to permit changing of the table structure, if desired, and the leather facing 23 is also removable so as to permit its replacement when it becomes worn.

20 2e In use, power is transmitted to the shaft 26 from any suitable prime mover (not shown) which rotates the drum 27 and the table 2 is adjusted relative to the cylinders 28 by means of the adjusting screw 18 in accordance with the thickness of the hides to be glazed, and the hides are passed over the table structure 2 and between the facing 23 and the glazing agates or cylinders 28 permitting the glazing of the entire surface 25 of the hide by its feeding through the machine and eliminating the movement of the hide above over the table to bring various parts thereof in active relation to the glazing cylinder, such as is done in approved 30 types of glazing machines now in use, thereby saving considerable time and labor in the proper glazing of hides.

It is, of course, to be understood, that the invention may be constructed in various 40 other manners, and the parts associated in different relations, and therefore, we do not desire to be limited in any manner, except as set forth in the claims hereunto appended.

45 What we claim is:—

45 1. In a leather glazing machine, the combination of a supporting structure having a drum transversely journaled thereon intermediate its ends, a plurality of glazing cylinders detachably carried by said drum, a 50 receiving table pivotally connected to said supporting structure at one end thereof, spring means and tension rods therefor interposed between said supporting structure and table on opposite sides and adjacent the free ends thereof, said spring means urging 55 said table upwardly from one end of said supporting structure, threadedly adjusted slideable wedge means carried by said supporting structure and extended inwardly 60 from one end of said structure, pivoted wedge members coengaging with the slideable wedge members, said pivoted wedge members being adjustably connected to said tension rods for retaining said receiving table in a fixed position relative to said glaz-

ing cylinders, said cylinders being disposed in parallel rows in staggered relation to overlap in their surface engaging paths of travel substantially as described.

2. In a leather glazing machine, a table, a drum rotatable over said table, longitudinal series of spaced bearing members on the drum, each of said members including two cooperating jaws, a glazing cylinder arranged between the jaws of each bearing member, adjustable binding means for the respective pairs of jaws and the glazing cylinders in each row being disposed to bridge the space between the cylinders in the adjacent row.

3. In a leather glazing machine, a table, a drum rotatable over said table, a plurality of spaced glazing cylinders carried by said drum and arranged in longitudinal rows on the drum, spring means urging the table in the direction of the drum, and wedge means for adjusting the table in an opposite direction.

4. In a leather glazing machine, a support, a table hingedly secured to the support, a drum rotatable over the said table, a plurality of spaced glazing cylinders carried by said drum and arranged in longitudinal rows on the drum, spring means adjustably arranged between the table and support, for urging the table in the direction of the drum, and wedge means guided on the support, and operating means for said wedge means for moving the latter to influence the spring means for regulating the adjustment of the table with respect to the drum.

5. In a leather glazing machine, a support, a table hingedly secured thereto, a drum having spaced glazing cylinders thereon arranged for rotation above the table, spring influenced means carried by and depending from the table, pivoted means on the support to which the spring means is adjustably secured, wedging means guided on the support and engageable with the pivoted means, and adjustable means revoluble on the support and associated with the wedge means for influencing the latter to regulate the tension of the spring means.

6. In a leather glazing machine, a support, a table hingedly secured to the support, said table having angle sides and a bed between said sides, a drum journaled on the support and arranged above the table and designed to be continuously rotated in one direction, a plurality of spaced glazing cylinders carried by the drum and arranged in longitudinal rows on the drum, spring influenced rods adjustably secured to the sides of the bed, pivoted members on the support through which the rods pass and to which the rods are adjustably secured, said members having beveled corners, wedge members guided on the support and engaging the said

beveled corners of the said members, and wheel operated means for imparting a longitudinal movement to the wedge members, for the purpose set forth.

5 7. In a leather glazing machine, the combination with a table, of a glazing member mounted above the table and in operative position thereto, spring means for supporting the table and means including a man-

ually adjustable wedge for adjusting the table away from the glazing member against the tension of said spring means.

In testimony whereof we affix our signatures.
